RADIOMETER

David R. Estes, Mountain View, Calif., assignor to
Physics International Company, San Leandro,
Calif., a corporation of California

Filed Mar. 29, 1968, Ser. No. 11,201

Term of patent 14 years

Int. Cl. D10—II

U.S. C. D52—6

Fig. 1

Fig. 2

Fig. 3

Fig. 4

FIGURE 1 is a front and left side view in perspective of a radiometer showing my new design.

FIGURE 2 is a front view.

FIGURE 3 is a view of the right side, and

FIGURE 4 is a rear view.

The essential features of the design reside in the solid line portions.

I claim:

The ornamental design for a radiometer, as shown and described.
